UNITED STATES PATENT OFFICE.

HENRY C. MANCHESTER, OF SCRANTON, PENNSYLVANIA.

RAILWAY-CAR WALL CONSTRUCTION.

1,410,697.

Specification of Letters Patent. Patented Mar. 28, 1922.

Application filed July 3, 1919. Serial No. 303,391.

To all whom it may concern:

Be it known that I, HENRY C. MANCHESTER, a citizen of the United States, residing at Scranton, in the county of Lackawanna and State of Pennsylvania, have invented 5 certain new and useful Improvements in Railway-Car Wall Constructions, of which the following is a specification.

My invention relates to the construction 10 of railway cars, particularly freight cars, and the principal object of the invention is to provide a wall panel to constitute the end of the car, for example, or part of it, composed of a metal sheet or plate manufactured 15 by a hot rolling process and formed with solid ribs suitably placed so as to give the panel strength and stiffness without excessive weight, sufficient to withstand the stresses to which the wall of the car is subjected, for example, when the panel is used 20 for the end of a car, sufficient to withstand the cargo thrusts and weaving stresses to which the end wall of the car is subjected under service conditions.

25 A further object is to provide a metal car wall panel of the character described in association with a suitable lining made of wood or other like material.

In general, the invention provides a wall 30 structure for a freight car which is relatively light, inexpensive to manufacture, and readily applied either to old cars, for repair purposes, or to new cars in the process of construction.

35 The invention is illustrated, in certain preferred embodiments in the accompanying drawings, wherein:

Fig. 1 is an end elevation of the superstructure of a railway box car provided with 40 an end wall constructed in accordance with my invention;

Fig. 2 is a sectional plan on line 2—2 of Fig. 1;

Fig. 3 is a fragmentary side elevation of 45 the end portion of the car superstructure;

Fig. 4 is a vertical sectional view on line 4—4 of Fig. 1;

Fig. 5 is a fragmentary detail section of one of the attaching members for securing 50 the panel to the frame of the car;

Fig. 6 is a sectional plan view similar to Fig. 2, showing a modified form of the invention applied to a car of steel construction; and

55 Figs. 7 and 8 are sectional plans illustrating further modifications.

It will be realized that the invention may be embodied in constructions differing considerably in their structural details from those described and claimed in this application. In Figs. 1 to 5, inclusive, and 7 and 8, I have shown and will describe suitable embodiments of the inventive idea as applied to a car the superstructure of which is largely made of wood. The invention might 60 be applied, with certain obvious modifications, to a car of metal construction.

In Figs. 1 to 5, inclusive, of the drawings, 10 designates the end sill of the car, 11 the end plate, 12 the side plates, 13 the side sills, 14 the flooring and 15 the side sheathing.

The end wall of the car consists, in the embodiment of the invention shown in these figures, of a single rolled metal plate 16, although obviously a plurality of plates suitably overlapped and secured together to provide strong, waterproof joints between them might be used instead of the single plate. The plate 16 is formed during the rolling process with a plurality of solid ribs 17 80 which are shown as parallel to each other and extending across the plate horizontally from edge to edge thereof. The plate is also formed with a plurality of similar ribs 18 on its inner surface, the latter being preferably in staggered arrangement with the ribs 17 on the outer surface. The plate 16 is secured in any suitable manner, for example, by bolts 19, to the end sill 10 and end plate 11 of the car framing. The vertical edges of 85 the plate are secured to the car body by means of angular members 20 which, in this construction, take the place of the ordinary end posts, the end flanges 21 of the angular members being formed at suitable intervals 90 with slots 22 through which the ribs 17 may project, and the end plates being riveted to the angles on each side of each rib 17. The side flanges 23 of the attaching angles 20 are preferably secured to the longitudinal frame 100 members of the car, that is, to the side plates 12 by gussets 24, and to the side sills 13 by gusset plates 25. If the car is provided with belt rails, as indicated at 26 in the drawing, the attaching flanges may be secured to these 105 belt rails by gussets 27.

To provide a lining for the end wall plate 16 boards 28 are secured to the inner surface of the plate between the ribs 18 by means of bolts 29, or other fastening devices, the 110 boards preferably being thick enough to project beyond the ribs. This arrangement

makes an effective lining which is inexpensive to construct.

In the modified construction shown in Fig. 6, the ribs 18^a on the inner surface of the sheet 16^a terminate within the edges of the sheet. The ribs 17^a on the outer surface of the sheet preferably extend to the edges of the vertical sheet and these edges are bent at right angles to the body portion of the sheet 10 to provide attaching flanges 30 which may be secured to the metal side sheets 31 of the car by rivets 32.

Fig. 7 illustrates a modification, similar to that of Fig. 6, applied to a car of wood 15 construction. In this form of the invention the inner ribs 18^b of the end sheet 16^b preferably terminate within the edges of the sheet at points adjacent the corner posts 33.

The attaching flanges 30^a overlap the 20 side sheathing 15^b of the car and are secured to the corner posts 33 by bolts 34, 35, which pass through the corner posts. The ends of the lining boards 28^b preferably abut against the inner face of the corner 25 posts. By having the lining boards positioned in this manner, and by having the edges of the sheet overlap the side of the car, the wood framing of the car is effectively reinforced and rigidified.

30 In Fig. 8, the ribs 17^c on the outer surface of the sheet terminate within the edges of the sheet and the flat margins 36 overlap the side of the car and are secured thereto by bolts 34, 35. In other respects, the 35 end sheet construction shown in this figure may be the same as that shown in Fig. 7 and corresponding parts thereof have accordingly been designated with like reference characters.

40 I claim:

1. In a railway car, a wall panel consisting of a rolled metal plate formed with a plurality of integral parallel strengthening ribs on the inner surface of the same and 45 spaced apart distances considerably greater than the thickness of said ribs, in combination with lining boards attached to the plate between said ribs and filling the recesses formed thereby.

50 2. In a railway car, a wall panel consisting of a metal plate rolled to form integral strengthening ribs on opposite sides of the plate, in combination with lining boards attached to the inner surface of the plate between the ribs thereon.

3. In a railway car, a wall panel consisting of a metal plate rolled to form integral strengthening ribs on opposite sides of the plate, those on one side being in staggered 60 relation to those on the other, in combination with lining boards attached to the in-

ner surface of the plate between the ribs thereon.

4. In a railway car, a wall panel consisting of a rolled metal plate formed with 65 strengthening ribs spaced apart distances considerably greater than the thickness of the ribs, and boards attached to one side of the plate between the ribs thereon and projecting beyond the same. 70

5. The combination with the framing of a railway car, of a rolled metal end panel extending across the end of the car between oppositely disposed framing members and formed with a plurality of integral solid 75 angularly projecting strengthening ribs on opposite sides of the plate, those on one side being in staggered relation to those on the other.

6. The combination with the framing of 80 a railway car, of a rolled metal end panel extending across the end of the car between oppositely disposed framing member and formed with a plurality of integral solid parallel angularly projecting ribs on the 85 inner surface thereof and spaced apart distances greater than the thickness of the ribs, means for attaching said plate to the car framing, and lining boards secured to the plate between said ribs. 90

7. In combination with the framing of a railway car, of a pair of upright angle bars at the corners of the end of the car, the end flanges of which are formed with horizontal slots, a rolled metal plate attached to said 95 angles and formed with solid, horizontally disposed ribs which project through said slots and with ribs on the inner surface of the plate in staggered relation with the aforesaid ribs, and lining boards attached to 100 the inner surface of the plate between the ribs thereon.

8. The combination with the framing of a railway car, of a wall panel consisting of 105 a rolled metal plate formed on opposite sides, by rolling, with a plurality of solid, integral, angularly projecting ribs.

9. The combination with the framing of a railway car, of a wall panel consisting of 110 a rolled metal plate formed on opposite sides, by rolling, with a plurality of solid, integral, angularly projecting ribs, the ribs on one side of the plate being in staggered relation with those on the other side.

10. The combination with the framing of 115 a railway car, of a wall panel consisting of a rolled metal plate formed on opposite sides, by rolling, with a plurality of solid, integral angularly projecting ribs which are substantially parallel and extend across 120 the plate from edge to edge.

HENRY C. MANCHESTER.
